BALLOON GIRDLE

Kenneth M. McLellan, Lakewood, Ohio, assignor
to Industrial Rayon Corporation, Cleveland,
Ohio, a corporation of Delaware

Application January 21, 1944, Serial No. 519,133

3 Claims. (Cl. 57—168)

This invention relates to the twisting of yarns or threads and it provides a method and apparatus for restricting the ballooning of yarn or thread in the course of the twisting operation.

In the twisting of yarn or thread it is customary to feed the yarn or thread through a suitable guide such as, for example, a pigtail guide to a rotating collecting package, the rotation of the package being such that the yarn when collected thereon will be twisted. The twisting operations are usually carried out at relatively high speeds with the result that the yarn in passing from the pigtail guide to the collecting package will be subjected to centrifugal action which causes the yarn to "balloon." This "ballooning" action is not too objectionable if the maximum diameter of the balloon remains relatively small. However, if the balloon diameter is of substantial size, the amount of space required by any one collecting package used in the twisting operation will be excessive. From the standpoint of economy in space, it is desirable to conduct the twisting operations by having the twisting spindles upon which the collecting packages are mounted as close together as possible without interfering with the efficiency of the operation. To achieve this objective, therefore, it is important to keep the maximum balloon diameter as small as practicable. In general, an increase in the weight or denier of the yarn being twisted will tend to increase the ballooning effect.

With the method and apparatus of this invention, excessive ballooning of yarn or thread in the twisting operation can be readily prevented. The apparatus of the invention is of simple construction, does not interfere with the normal operation of the twisting apparatus and permits ready access to the thread or yarn in the event of a break or stoppage. These results are achieved without imposing any undue frictional resistance upon the yarn being twisted.

It has been observed that when the collecting package for the twisted yarn is relatively empty, the maximum ballooning diameter of the yarn will be found in a certain plane and that when the collecting package is substantially full the maximum ballooning diameter will be found in a different plane. In addition, the latter ballooning diameter may or may not be the same as the former. The method of controlling ballooning in accordance with this invention embraces the steps of determining the location of these planes of maximum ballooning diameters and then confining the thread in substantially each of these planes to generally circular orbits of smaller di-

ameters than the corresponding circular orbits of maximum ballooning diameters, the balloon of the thread being subjected to no other confining action.

5 The invention will be more fully described by reference to the accompanying drawing which shows the application of one embodiment of the invention to a cap twister although it is to be understood that the invention is not to be limited to this embodiment. In the drawing,

Figure 1 is an elevation of a plurality of cap-twisting units to which thread is supplied by a thread-advancing, thread store device;

15 Figure 2 is a plan view of one twisting unit along the line 2—2 of Figure 1 showing the position of the balloon restraining girdle with respect to the cap twister;

Figure 3 is a perspective view of the balloon restraining girdle itself; and

20 Figures 4 and 5 are diagrammatic representations of the balloon peripheries with and without the balloon restraining girdle of the invention. Referring to the drawing, the cap-twisting units illustrated in Figure 1 represent a fragmentary portion of the cap-twisting section of a machine for producing rayon by the continuous processes as shown and described, for example, in G. P. Torrence et al., Patent No. 2,284,497, in which rayon yarn is supplied to the cap twister 20 by means of a thread-advancing reel such, for example, as that shown and described in Knebusch, Patent No. 2,210,914, or Jordan Patent No. 2,210,920. A cap member 1 is mounted on a fixed spindle 2 extending through a traverse member or lifting rail 3a which is rigidly secured to the base member 3. A pulley 4 is mounted in a suitable manner on the lifting rail 3a to rotate about spindle 2. The pulley may have a sleeve extension or similar means upon which the spool or bobbin 5 will fit so that it will rotate with the pulley. The lifting rail 3a moves the rotating bobbin into and out of the cap 1 as yarn supplied by means of the thread-advancing reel 6 is led through a pigtail guide 7 to the bobbin.

45 Due to the rapid rotation of the bobbin the thread balloons around the cap as illustrated, for example, in Figures 4 and 5. As there shown, the yarn between the pigtail guide 7 and the lower edge of cap 1 assumes the various transitional ballooning contours shown by the lines c, d, e, and f. Contour c is attained when the bobbin on which the thread is being collected is substantially empty. As the bobbin is being filled, the ballooning contour changes to that

shown by curves *d* and *e*, respectively, and finally assumes that shown by curve *f* when the bobbin is substantially full of twisted yarn. The maximum ballooning diameter when the bobbin is substantially empty occurs in a plane passed horizontally through the line AA'; the maximum ballooning diameter when the bobbin is substantially full occurs at a higher level in a plane passed horizontally through the line BB'.

The balloon restraining girdle of the invention restricts the orbit of the balloon in the horizontal planes at the levels indicated by lines AA' and BB'. This girdle is composed of two substantially circular rings *10* and *11* having diameters such that the ballooning will be restricted the desired amount. Attached to each of the rings are extension members *13* (see also Figs. 2 and 3) which are threaded at their ends. The threaded portions are passed through the separating shields *8* between adjacent cap-twisting units and are secured to these shields by means of nuts *13a*.

The rings *10* and *11* are joined at spaced intervals around their circumferences by outwardly curved arcuate members *12*. The rings are open at *15* and one pair of the ends of the rings is joined together at *16* to form an outwardly curved lip *14*. The opening *15* permits the operator to remove yarn freely from within the girdle or to insert it therein. The opening is relatively small and has no adverse effect on the yarn which is being twisted.

The effect of the two rings composing the girdle on the ballooning of the thread is shown at the right side of Figure 5. As the bobbin on which the yarn is being collected passes from the substantially empty to the substantially full stage, the ballooning contour of the yarn changes from that shown by curve *g* to that shown by curves *h* and *i* and finally assumes that shown by curve *j*.

The ballooning range indicated by the lines AA' and BB' will, of course, vary depending upon the nature of the material being twisted, the conditions of twisting, etc. As a consequence, the spacing of the rings of the balloon girdle may require adjustment in order to achieve their greatest effectiveness in a particular twisting operation.

The wear on the rings of the girdle may sometimes be unequal. It will be noted from Figure 1, however, that the girdle members are mounted on the separating shields *8* of adjacent cap-twisting units in such a manner that the extensions *13* attached to each of the rings are always above or below the extension members of the girdle in the adjoining compartment. As a result, the girdle may be turned over or reversed in the event of a change in twisting direction, or uneven wear of its rings thereby extending its usefulness.

It may be desirable to have one of the girdle rings of a greater diameter than the other in order to equalize wear on the ring members and

to otherwise facilitate operations. The rings themselves may be made of any suitable material which does not have an adverse abrading action on the yarn with which it comes into contact.

5 The ends of the rings adjacent to the opening *15* need not be joined together by means of a curved member *12* but may instead be left free. In such case, however, it is desirable to curve the ends so as to facilitate introduction of yarn into the rings.

10 Reference to yarn in the specification and claims is intended to include generally any filamentous material which may be subjected to a twisting operation such as, for example, thread or thread-like materials, ribbons, thin bands, etc.

15 Since, in general, only two rings are required in the girdle, the desired balloon restraining action may be accomplished with a minimum amount of friction between the girdle and the yarn being twisted.

20 Although the foregoing description of the invention has reference to the use of the balloon girdle in connection with a cap twister, it is to be understood that the invention may also be used in connection with other types of twisting operations such as, for example, ring twisting, up twisting, down twisting, etc.

I claim:

25 1. A balloon restraining girdle comprising at least two substantially circular co-axial rings spaced one above the other to cover a rotating yarn ballooning range, said rings having openings one above the other, one set of ends of said rings being joined forming an outwardly extending lip tangent to said rings, a plurality of outwardly curved supporting members joining said spaced rings, and elongated members projecting from each of said rings in substantially the planes of said spaced rings.

30 2. A balloon restraining girdle comprising at least two substantially circular co-axial rings spaced apart to cover a rotating yarn ballooning range, said rings having peripheral openings one above the other, a pair of extension members attached to each of said rings, the pair of extension members attached to one ring extending in a direction opposite to that of the extension members attached to the other ring.

35 3. A cap-twisting assembly comprising a plurality of cap-twisting units each of which includes a thread guide, a cap and a rotating yarn collecting means, separating shields between said twisting units, a balloon restraining girdle positioned around but spaced from said cap, said girdle consisting of at least two spaced substantially circular rings, said rings having peripheral openings one above the other, each of said rings also being provided with a pair of extension members, the pair of extension members on one ring projecting in a direction opposite to that of the extension members of the other ring, the ends of said extension members being secured to said separating shields.

KENNETH M. MCLELLAN.
